UNITED STATES PATENT OFFICE.

GEORGE F. EARNSHAW, OF CHICAGO, ILLINOIS, ASSIGNOR TO EARNSHAW KNITTING COMPANY, A CORPORATION OF ILLINOIS.

TWISTLESS TAPE.

1,100,060.

Specification of Letters Patent. Patented June 16, 1914.

Application filed December 18, 1912. Serial No. 737,446.

To all whom it may concern:

Be it known that I, GEORGE F. EARNSHAW, a citizen of the United States, residing at Chicago, in the county of Cook and State 5 of Illinois, have invented certain new and useful Improvements in Twistless Tapes, of which the following is a specification.

This invention relates in general to fabrics and more particularly to narrow fabrics 10 commonly known as tapes.

Tapes are very desirable for securing infants' shirts and other garments in position on the body of the wearer instead of using pins or buttons which are uncomfortable to 15 the wearer and pins particularly are apt to injure the wearer in case they become unfastened, or in case sufficient care is not exercised in inserting them.

The advantage of using tapes for this purpose 20 instead of buttons and pins has long been recognized, but the principal objection to the use of tapes resides in the fact that after the garment is washed the ordinary tape will twist or curl up so that it cannot 25 be readily tied.

My present invention aims to produce a tape which will not twist or curl up when the garment is washed.

My invention will be best understood by 30 reference to the following description when considered in connection with the accompanying drawings throughout the various views of which like reference characters refer to similar parts.

Referring to the drawings: Figure 1 is a 35 plan view of a section of a tape embodying my invention; Fig. 2 is a fragmentary section, on an enlarged scale, of the tape shown in Fig. 1.

Tapes as employed prior to my invention 40 have been woven of warp and weft threads both twisted in the same direction, with the result that when the tape is wet the twisting of threads will be increased and the tape 45 will curl up. The tape 5 illustrated in Figs. 1 and 2 of the drawings comprises warp threads 6 twisted in one direction and weft

threads 7 formed of a continuous thread twisted in the opposite direction. While in Fig. 2 I have shown the warp threads as 50 twisted in right-hand direction and the weft threads as twisted in left-hand direction, it will be obvious that the warps might be left-hand twisted threads and the wefts right-hand twisted threads. In any event, the 55 twist of the warp and weft threads lies in opposite directions so that when the twist is increased upon wetting of the fabric the tendency of the tape to twist in one direction by reason of the twisting of the warp 60 threads will be resisted by the twisting of the weft threads in the opposite direction and the tape, therefore, remains flat and in its original condition.

Any suitable material may be utilized for 65 the warp and weft threads, but, ordinarily, cotton or linen is employed. The material of which the threads are composed, however, is of relative unimportance so long as a portion, at least, of one set of the warp and 70 weft threads are twisted in a direction opposite to a portion, at least, of the other set of threads.

It is believed that my invention will be 75 fully understood from the foregoing without further description, and it will be obvious that by utilizing oppositely twisted threads for the warp and weft threads, I have produced a tape which will not twist or curl and will remain in its original flat condition re- 80 gardless of the number of times that the garment to which it is applied may be washed.

I claim:—

A woven tape consisting of interwoven 85 warp and weft, the warp comprising a series of threads twisted in one direction, and the weft comprising a continuous thread twisted in a direction opposite to the direction of twist of the warp threads.

GEORGE F. EARNSHAW.
